UNITED STATES PATENT OFFICE.

RUDOLPH DE BOER, OF GRAND RAPIDS, MICHIGAN, ASSIGNOR TO GRAND RAPIDS METALCRAFT CORPORATION, OF GRAND RAPIDS, MICHIGAN, A CORPORATION OF MICHIGAN.

DESIGN FOR A WALL POCKET OR SIMILAR ARTICLE.

Application filed March 7, 1929. Serial No. 30,379. Term of patent 7 years.

To all whom it may concern:

Be it known that I, RUDOLPH DE BOER, a citizen of the United States, residing at Grand Rapids, in the county of Kent and State of Michigan, whose postal address is No. 22 Commerce Avenue, S. W., Grand Rapids, in the county of Kent and State of Michigan, have invented a new, original, and ornamental Design for Wall Pockets or Similar Articles, of which the following is a specification, reference being had to the accompanying drawing, forming a part thereof, in which:

Fig. 1 is a front elevational view of the wall pocket showing my new design; and

Fig. 2 is a side elevational view thereof.

I claim:

The ornamental design for a wall pocket or similar article substantially as shown.

RUDOLPH DE BOER.
